HOLDING MEANS FOR LAMPS

Harry M. Bell, Ashley, Pa.

Application January 31, 1933. Serial No. 654,528

3 Claims. (Cl. 240—59)

This invention relates to a holding means for lamps and has relation more particularly to a device of this general character intended to be carried by a belt and which engages a lamp or similar device in a manner to hold such lamp or device in fixed position upon the belt. It is primarily an object of the invention to provide a device of this kind especially designed and adapted for use in connection with miners' lamps.

10 The invention consists in the details of construction and in the combination and arrangement of the several parts of my improved holding means for a lamp whereby certain important advantages are attained and the device rendered 15 simpler, less expensive and otherwise more convenient and advantageous for use, as will be hereinafter more fully set forth.

The novel features of my invention will hereinafter be definitely claimed.

20 In order that my invention may be the better understood, I will now proceed to describe the same with reference to the accompanying drawing, wherein:—

Figure 1 is a view in elevation of a holding 25 means constructed in accordance with an embodiment of my invention, the coacting loop of the lamp or the like being in section;

Figure 2 is a view in top plan of the structure as illustrated in Figure 1, the lamp being diagrammatically indicated by broken lines with the rear or back wall in full lines;

Figure 3 is a sectional view taken substantially on the line 3—3 of Figure 1;

Figure 4 is a view in elevation showing the 35 relative positions of the parts of the holding means controlling either the securing or separating operation;

Figure 5 is a view in perspective of the elongated member or plate as herein comprised;

40 Figure 6 is a view in perspective of the keeper as herein disclosed.

As disclosed in the accompanying drawing, B denotes a belt or waist encircling member of any desired type and W the back wall of a miner's lamp which is provided at its upper part with a transversely disposed rigid loop L with which my improved holding means is adapted to coact for effectively maintaining the lamp in a fixed position upon the belt B.

50 My improved holding means as herein disclosed comprises an elongated plate 1 of desired dimensions having one end defined by a flange 2 substantially at right angles to the plate or member 1 and the outer marginal portion of the flange 2 is defined by an outwardly disposed flat

strip 3 substantially at right angles to the flange 2 and of a length to project beyond opposite sides of the plate or member 1. The strip 3 is flat and is secured, as at 4, to the belt B in any desired manner, such as for example by rivets. 60 The opposite end portion of the member or plate 1 has a returned portion 5 lapping the inner or rear face of the plate or member 1 and spaced therefrom.

Adjacent portions of the member or plate 1 and the returned portion 5 or lip as it may be called are provided with a notch extending through the returned bend a whereby an opening 6 is provided for the finger 7 of a keeper K. The keeper K as herein disclosed comprises a strip 8 riveted, 70 as at 9, or otherwise secured to the belt B, and a marginal portion of the strip 8 is provided with a reverted flange 10, the returned portion b of which having projecting from its free longitudinal margin the finger 7 hereinbefore referred to. 75 This finger 7 as herein disclosed is integral with the returned portion b of the keeper K and is substantially coplanar therewith.

The finger 7 is in the form of a reversed L with the outer heel portion c cut on a diagonal line. 80 The foot portion d of the finger 7 is of a width substantially equal to the length of the opening 6 of the member or plate 1 so that when the plate or member 1 is engaged with the keeper K rattling is substantially eliminated.

In practice, the member or plate 1 is inserted through the loop L of the back wall of the lamp and then the plate or member 1 is so manipulated as to direct the finger 7 through the opening 6. In order to do this the portion of the belt between the strips 3 and 5 must be so flexed as to allow the plate or member 1 to be transversely inclined with respect to its longitudinal axis whereupon the desired connection between the member or plate 1 and keeper may be readily effected. This connection between these two parts is further facilitated by the fact that the opening 6 of the member or plate 1 is of a length in excess of the length of the leg e of the finger 7. 90

A holding means such as hereinbefore described is of particular advantage as it serves to maintain the lamp or kindred device in substantially a fixed position upon the belt and more especially with respect to the body of the person wearing the belt so that no hindrance or obstruction is afforded by the lamp to the wearer in the movements of his body incident to his work.

When the plate or member 1 is engaged with the keeper K, the returned portion or lip 5 of 110

the plate or member 1 interfits between the portions of the reverted strip 8. In order to assure the portions of the reverted strip being maintained separated an end portion of the reverted strip is provided with a finger 11 overlying the strip 8, the free end portion of said finger 11 carrying a flange 12 disposed toward the strip 8 for direct contact therewith.

From the foregoing description it is thought to be obvious that a holding means for a lamp constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereininafter claimed.

I claim:

1. A holding means comprising, in combination, an attaching member, a plate, a strip carried by one end portion of the plate and secured to the attaching member, said plate being offset with respect to the strip, the opposite end portion of the plate having a returned lip, the bent portions of the plate and lip being cut out to provide an opening, a keeper comprising a strip secured to the attaching member at a point spaced from the attaching strip of the plate, a reverted flange carried by the strip of the keeper, and an angular arm carried by the free marginal portion of the flange for insertion through the opening of the plate, the portion of the attaching member between the strip of the plate and the strip of the keeper being flexible to allow the plate to be angularly disposed to facilitate the engagement or removal of the plate with respect to the keeper.

2. A holding means comprising, in combina-

tion, an attaching member, a plate, a strip carried by one end portion of the plate and secured to the attaching member, said plate being offset with respect to the strip, the opposite end portion of the plate having a returned lip, the bent portions of the plate and lip being cut out to provide an opening, a keeper comprising a strip secured to the attaching member at a point spaced from the attaching strip of the plate, a reverted flange carried by the strip of the keeper, and an angular arm carried by the free marginal portion of the flange for insertion through the opening of the plate, the portion of the attaching member between the strip of the plate and the strip of the keeper being flexible to allow the plate to be angularly disposed to facilitate the engagement or removal of the plate with respect to the keeper, the lip of the plate meshing with the reverted flange of the keeper when the plate is engaged with the keeper.

3. A holding means comprising, in combination, an attaching member, a plate, a strip carried by one end portion of the plate and secured to the attaching member, said plate being offset with respect to the strip, the opposite end portion of the plate having a returned lip, the bent portions of the plate and lip being cut out to provide an opening, a keeper comprising a strip secured to the attaching member at a point spaced from the attaching strip of the plate, a reverted flange carried by the strip of the keeper, an angular arm carried by the free marginal portion of the flange for insertion through the opening of the plate, the portion of the attaching member between the strip of the plate and the strip of the keeper being flexible to allow the plate to be angularly disposed to facilitate the engagement or removal of the plate with respect to the keeper, and means carried by the outer portion of the reverted flange and coacting with the strip of the keeper to maintain spaced the portions of the reverted flange.
